SHUTTLE VALVE

Filed Nov. 24, 1942

UNITED STATES PATENT OFFICE

2,440,478

SHUTTLE VALVE

Ottmar A. Kehle, West Los Angeles, Calif., assignor to Adel Precision Products Corp., a corporation of California

Application November 24, 1942, Serial No. 466,784

2 Claims. (Cl. 251—118)

1

This invention relates to hydraulic systems for operating aircraft controls and the like and more particularly pertains to a shuttle valve for adapting a system of this nature to immediate operation by means of a motor driven hydraulic pump or a hand operated hydraulic pump.

A primary object of my invention is to provide an improved and highly efficient shuttle valve of the character described which when connected in a hydraulic system including a hand pump and a rotor driven pump, will cut out of the system the hand pump and connect in the system the motor driven pump responsive to the operation of the latter and likewise cut out the motor driven pump and cut in the hand pump incident to operation of the hand pump upon cessation of operation of the motor driven pump whereby in case of failure of the motor driven pump the system may be instantly operated by means of the hand pump, the shuttle valve being of simple construction, light as to weight, reliable in operation and instantly responsive to the operation of the two pumps to insure a reliable operation of the system at all times.

Another object of my invention is to provide, for a shuttle valve of the character described, spring actuated detents which will not only possess the usual shuttle valve control features but, in addition, will function to offset the effect of wear upon the valve and valve seats, so that the valve will seat in a leakproof manner even after it has been in operation for a long time.

Another object of my invention is to provide a shuttle valve of the character described in which a casing or housing, two inlets, an outlet means, a shuttle valve and a spring loaded detent means are constructed and arranged so that under all operating conditions and at all times and especially when the shuttle valve is being shifted from either seated position to its other seated position only one of said inlets will be open at a time thereby positively preventing both inlets from having communication with the outlet means at the same time as well as preventing any interflow between said inlets.

With the foregoing objects in view, together with such other objects and advantages as may subsequently appear, the invention resides in the parts and in the combination, construction and arrangement of parts hereinafter described and claimed and illustrated by way of example in the accompanying drawing, in which:

Fig. 1 is a part front elevational-part sec-

2

tional view of a shuttle valve embodying my invention;

Fig. 2 is a sectional view taken on the line 2—2 of Fig. 1;

Fig. 3 is a part top plan-part sectional view of the valve;

Fig. 4 is a fragmentary view partly in end elevation and in part sectioned on the line 4—4 of Fig. 1;

10 Fig. 5 is a front elevation of the valve;

Fig. 6 is a diagrammatic view of a hydraulic system showing the operation of the shuttle valve.

Referring to the drawing more specifically, 15 1 designates an elongated valve body member of a shuttle valve unit embodying my invention and provided with a valve-receiving bore 8 extending longitudinally therethrough. The ends of this bore are closed by screw threaded plug and 20 valve seat members 9 the inner end portions of which constitute tubular valve seat members 10 and 11.

Extending angularly (downward as seen in Figs. 1 to 4 hereof) from and formed integral 25 with end portions of the valve body member 7 are tubular connections 12 and 13 through which pressure fluid intake ports 14 and 15 extend into the end portions of the bore 8 so that pressure fluid may be delivered to either end of said bore.

30 The intake ports 14 and 15 open into counterbores 16 in the bore 8 as shown in Figs. 1 and 4. These counterbores register with radial ports 17 in the tubular valve seat members 10 and 11 and said radial ports are in communication with axial 35 bores 18 afforded by said tubular seat members, whereby pressure fluid may pass through said seat members into the bore 8 proper.

Depending from and formed integral with the valve body member at a point approximately 40 centrally of the end thereof is a box-like outlet connection 19 (Figs. 2 and 4) providing a pressure outlet port 20 which is communicated with the bore 8 by means of ports 21 and 22.

In the elongated valve chamber afforded by 45 the bore 8 is a reciprocable shuttle valve generally designated 23 and provided with piston-like valve members 24 and 25 at its ends and cam surfaces 26 and 26' between its ends. These valve members have a working fit in the bore 8 50 and are adapted to seat one at a time. In one position of the shuttle valve the valve member 24 thereon will seat against the seat member 10 while the valve member 25 is removed from the seat member 11, whereas in the other position 55 of the shuttle valve, the valve member 25

is seated on the seat member 11 while valve member 24 is unseated.

When pressure fluid is introduced for example through the intake port 14 and the valve member 24 is seated on the seat member 10, there being at this time no fluid flow through the other intake port 15, the shuttle valve will be shifted to the right into position shown in Fig. 1 whereby the fluid will flow past the then unseated valve member 24 and out through the port 21 and outlet port 20. Upon now shutting off the flow of pressure fluid through the port 14 and introducing pressure fluid through the port 15 the position of the shuttle valve is reversed and valve member 24 will seat while valve member 25 unseats, thereby allowing free flow of fluid from the port 15 past the open valve member 25, through bore 8, port 22 and outlet port 20.

Means is provided for effecting a snap action of the shuttle valve and for releasably holding said valve in its seated positions. As here shown this means includes the cam surfaces 26 and 26' and a pair of spring loaded detents 27. These detents are mounted in tubular extensions 28 of the body member 8 and held therein by means of adjustable plugs 29, the adjustment of which will vary the spring tension of said detents. These detents engage opposite sides of the cam formation on the shuttle valve so that in one position of the shuttle valve the detents rest on the cam surface 26 and urge the valve member 25 towards its seat 11 while in the other position of the shuttle valve the detents will engage the other and oppositely inclined cam surface 26', so as to urge the valve member 24 against the seat 10. The detents have conical cam engaging ends 27' and when the valve is shifted by the pressure fluid to an extent that the ends 27' of the detents ride over the narrow ridge 26'' between said cam surfaces, the detents operate as cams to quickly effect a snap movement of the shuttle valve to the limit of its travel in the direction in which it is being shifted by the fluid pressure, thereby providing an instantaneous shifting and a fully responsive action of the valve unit to the shifting of the flow of pressure fluid. From Fig. 3 it is to be clearly seen that valve seat wear compensation is provided for by reason of the fact that the portions 27' of the spring pressed detents 27 can engage one cam face only, in such manner that the shuttle valve is urged against the seats, there being a clearance at such times at the opposite side of each detent to enable the detent fully to seat the valve even after the seats or the valves have become considerably worn. In other words, the oppositely inclined cam faces 25 and 26' which the detents engage, are sufficiently extensive and so positioned as to cause said detents to shift the valve an additional distance to compensate for wear.

One application of the shuttle valve unit hereof to a hydraulic motor system is shown in Fig. 6 wherein a reservoir A is connected by a line B to a motor driven hydraulic pump C which in turn is connected by a line D to the intake connection 13 and port 15 of my shuttle valve unit here generally designated E. A hand operated hydraulic pump F is supplied with fluid from the reservoir A through a line G and is connected by means of a line H to the shuttle valve intake connection 12. A pressure fluid line J leads from the shuttle valve outlet connection 19 to a suitable control valve K. Cylinder or motor lines L and M lead to opposite ends of a hydraulic motor

(cylinder) N and a return line leads from the control valve K to the reservoir.

As the motor operated pump C is normally used it is seen that the shuttle valve is normally in the position indicated in Fig. 6 with the valve member 25 unseated and valve member 24 seated so that the operating fluid will flow from the pump C, line D, connection 13, port 15, past the open valve member 25 into the bore 8 and thence through port 22, outlet port 20, line J, control valve K and one of the cylinder lines L and M to the hydraulic cylinder N, the fluid returning through the valve K and line to the reservoir.

Should the motor fail to operate or in case it is shut off and operation of the hand pump F is necessary or desirable, as soon as the operation of said hand pump is commenced, the pressure fluid therefrom flowing through the line H enters port 14 and is at once effective against the valve member 24 to shift the shuttle valve to unseat valve member 24 and seat valve member 25, thereby connecting the hand pump in the system and shutting off the connection of the motor operated pump to the system.

It will be seen that the outlet 20 is of a bifurcated character its pair of branches 21 and 22 communicating with the midlength part of the shuttle valve chamber at axially spaced apart points, and that said shuttle valve, when open to any extent, even slightly, will prevent by-passing of fluid from one to the other end portion of the bore through said paired port branches. This action and prevention of interflow is brought about by the cylindrical portions of the shuttle valve being so spaced apart as to be simultaneously engageable with the bore wall portions at opposite sides of the outlets 21 and 22 and disengageable with said bore wall portions one at a time to open the inlets and because said cylindrical portions remain in closing engagement with said bore wall portions on opposite sides of the outlets until the detent passes the apex of the ridge 26'' for engaging one or the other of the two cam surfaces 26 and 26' in each direction of movement of the shuttle valve.

While I have shown and described a specific embodiment of my invention I do not limit myself to the exact details of construction set forth, and the invention embraces such changes, modifications and equivalents of the parts and their formation and arrangement as come within the purview of the appended claims.

I claim:

1. In a valve of the character described, a casting having a cylindrical bore therethrough and an inlet seat at each end of the bore and an outlet means communicating with the bore intermediate of the seats, a shuttle valve slidable in the bore and having provision for alternately engaging the seats to open communication between a selected inlet and the outlet means and close the other inlet, said shuttle valve having a cylindrical portion at each end thereof engaging the wall of said bore inwardly of the respective inlet, said cylindrical portions being so spaced apart as to be simultaneously engageable with bore wall portions at opposite sides of said outlet means and disengageable with said bore wall portions one at a time to open the inlets, said shuttle having a central ridge flanked by two centrally and outwardly inclined surfaces, and a spring pressed detent disposed intermediate of said seats and in position for engaging one or the other of said inclined surfaces for urging the valve toward 70 and yieldably holding said valve against one or

the other of said seats, said cylindrical portions being positioned to remain in closing engagement with said bore wall on opposite sides of said outlet means until said detent passes the apex of said ridge in each direction of movement of the shuttle valve.

2. In a valve, a body member having a cylindrical bore therein, spaced inlet seats in said bore and outlet means communicating with said bore intermediately of said seats, a shuttle valve 10 glidable in said bore and having provision for alternately engaging said seats to open communication between a selected inlet seat and the outlet means and close the other inlet means, said shuttle valve having cylindrical portions engaging the wall of said bore inwardly of the respective inlet seats, said cylindrical portions being so spaced apart as to be simultaneously engageable with bore wall portions at opposite sides of said outlet means and disengageable with said bore wall portions one at a time to open said inlet seats, said shuttle valve having two cam surfaces, and a spring loaded detent disposed intermediately of said inlet seats for engaging one or the other of said cam surfaces for urging the shuttle valve toward and yieldably holding said valve against one or the other of said inlet seats, said cylindrical portions being positioned

to remain in closing engagement with said bore wall portions on opposite sides of said outlet means until said detent contacts one or the other of said cam surfaces in each direction of movement of said shuttle valve.
